(57) **CLAIM**

The ornamental design for a wheel fastener gauge as shown and described.

DESCRIPTION

FIG. 1 is a perspective view of a wheel fastener gauge according to our invention;

FIG. 2 is a front elevation view of the wheel fastener gauge in FIG. 1;

FIG. 3 is a bottom view of the wheel fastener gauge in FIG. 1;

FIG. 4 is a right-side view of the wheel fastener gauge in FIG. 1;

FIG. 5 is a left-side view of the wheel fastener gauge in FIG. 1;

FIG. 6 is a top view of the wheel fastener gauge in FIG. 1; and,

FIG. 7 is a bottom view of the wheel fastener gauge in FIG. 1.

The broken lines in the above figures illustrate elements that form no part of the claimed design for a wheel fastener gauge.

1 Claim, 7 Drawing Sheets
